DOFFING MECHANISM FOR FLIER SPINNING, DOUBLING, AND LIKE MACHINES.

Application filed January 29, 1926, Serial No. 84,663, and in Great Britain January 28, 1925.

This invention relates to spinning, doubling and like machines of the flier type having mechanical doffing mechanism in which it is found somewhat difficult to prevent the 5 drag washers from being displaced at one time or other during the carrying out of the doffing process. Our present invention consists in the application of means whereby the displacement of the washers is at all 10 times prevented while the same means afford facilities for retaining and moving the bobbins during certain parts of the doffing process which we now carry out by the employment of the novel devices hereinafter 15 explained.

In order that our said invention may be readily understood, we have hereunto appended sheets of drawings illustrative thereof in which:—

20 Fig. 1 is a front elevation showing the several parts of the machine in their respective positions during the spinning operations.

Fig. 2 is an end elevation of the parts 25 shown by Fig. 1 also in the positions they occupy as shown by said Fig. 1.

Fig. 3 is a similar end elevation to Fig. 2 but shows certain of the parts adjusted in their respective positions during one of 30 the first stages of the doffing process.

Fig. 4 is also a similar view to Fig. 3 but shows the next step in the process of doffing and the position that the several parts occupy after such step has been taken.

35 Fig. 5 shows certain of the parts illustrated by Fig. 4 readjusted ready for carrying out the replacing of the empty bobbins on the spindle.

Fig. 6 shows the several parts readjusted 40 in their respective positions just prior to their readjustment in position for the spinning actions to be recommenced, and before the cutting of the several threads is effected.

45 Figs. 7 and 8 are sectional end elevation and plan respectively and show our drag devices drawn to an enlarged scale.

Fig. 9 is a sectional end elevation of the 50 foot-step rail of the machine and our improved form of foot-step bearing for the spindle.

Fig. 10 is a plan of the machine's lifter rail and our drag-device with a spindle and a bobbin shown in section and in certain 55 relative positions hereinafter described.

Fig. 11 is a front elevation of the parts shown by Fig. 10.

Figs. 10 and 11 are drawn to a smaller scale than are Figs. 7, 8 and 9.

A indicates the end frames of the machine, and B the foot-step or supporting rail for the spindles. All the other parts shown by the drawings, and which are not herein-after referred to are of the ordinary and usual formation and construction. 60

It may be here observed that the doffing process and many of the movements of the devices for carrying same into effect to which our present invention relates are well known to those having a knowledge of the 65 spinning industry, so that we have herein-after only referred to same to such an extent as would clearly show wherein our novel devices differ from those previously employed for carrying out the removal of 70 the full bobbins (after the spinning operations had proceeded as far as desired) on the stopping of the machine and the supplying of empty bobbins to take their place prior to the restarting of the machine. 75

Further the kind of machinery in which our doffing apparatus has to be made use of is that known as "flier" spinning, doubling, twisting and like frames, wherein the fliers 80 4^a at all times revolve with the spindle 4 upon which they are fixed.

In carrying out our invention we employ a receptacle or holder 2 for the drag washers 3 (see Figs. 7 and 8) on each spindle 4 of the machine. 85

This holder 2 is preferably formed of sheet metal by the process of stamping although we are aware that it may be formed by casting or otherwise.

The holder 2 has a central opening for 90 the spindle 4 to pass through while it has projections 2^a formed on it to span the lifter rail 5 upon which it is loosely mounted and by which projections it is held against rotation by said lifter rail 5.

From the base of the holder 2 we have other projections 2^b arranged to extend vertically above same so as to hold or retain the drag washers 3 within while said drag washers are arranged to surround the 105 spindles 4 upon which the fliers 4^a are fixed. The vertical projections 2^b are situated laterally the spindle and are formed to have their upper ends a slightly lower than the upper surface b of the drag washer 3 upon which 110

the bobbin 6 rests, when mounted upon its spindle 4 while said projections 2^b are sufficiently far from the spindle as to be entirely clear of the base or flange of the bobbin 6, thus giving the bobbin 6 perfect freedom to rest upon the washers without being interfered with by said projections 2^b.

The spaces between the projections 2^b are to afford access to the washers 3 in order 10 that any accumulated fluffy or like matter may be readily removed by the attendant.

When using the washer holders 2 constructed as above described we arrange the lifter plate 5 to be slidable lengthwise the 15 machine while resting upon the upper ends of their lifter rods 7.

This is permitted by slots 5^a being made in the lifter plate 5 (see Fig. 10) to span the upper ends of the lifter rods 7 while yet 20 being supported by the flanges 7^a on said rods.

When the doffing has to commence, after the arresting of the machine and the adjusting of the lifter rail 5 and other parts as 25 above described, the attendant will operate the handle 40 to oscillate the shaft 41 so that by pinions 42 engaging racks 43 the step rail B carried by said racks, may be lowered in order to remove the foot-step bearings 44 30 clear of the lower ends of the spindles 4 in the usual manner.

After thus lowering the rail B we then lower the lifter rail 5 so that it and the drag washers 3 are clear of the lower ends of the 35 spindles 4, the attendant then slides said lifter rail 5 longitudinally by the handle 5^a in order to carry the washer holders 2 (along with the said lifter rail which is effected by a lateral flange 2^c taking into the openings 40 in the lifter rail 5 as shown by Fig. 7) so that the vertical projections 2^b on these holders 2 are brought beneath the flanges 6^a (see Fig. 11) at the lower ends of the bobbins 6 by which means certain portions of 45 said flanges will overhang said projections and thus afford spaces beneath said flanges for the insertion of the holding shoe 8 which may thus be brought into position to support said bobbin 6 upon its spindle 4 and 50 permit the lifter plate 5 to be further lowered out of the way of the spindles 4 as is shown (see Fig. 3). By this arrangement of the parts described bobbins 6 may on the removal of the shoes 8 be permitted to fall 55 or descend from their respective spindles 4 on to the pegs 9 fixed upon a peg rail 10 arranged to receive them as is shown by Fig. 3.

The moving forward of the spindles 4 from their operating positions shown by Fig. 60 2 to their advanced positions shown by Fig. 3 is effected by the supporting rail 11^a, which has the upper bearings 11 for the spindles 4 mounted upon it, being mounted to oscillate upon its bearings in well known manner; 65 the said movement of the rail 11 being ef-

fected by the handle device 12 which the attendant actuates to move the well known toothed quadrants 13 and 14 arranged in connection with the rail 11.

After the parts have been adjusted as 70 stated the attendant will then operate the handle 15 to bring the shoes or bobbin holders 8 from the position they occupy as shown by Fig. 3 into the rear position shown by Fig. 4 so that the bobbins 6 on the spindles 4 are permitted to fall or descend on to the pegs 9 as is before stated. When the bobbins have thus descended on to the pegs 9 he then moves the spindles a short space 75 forward by actuating the handle 12 after 80 which the rail 10 upon which the pegs 9 are fixed is turned upon its bearings (upon which it is mounted to oscillate) from the position shown in Fig. 3 into the position shown by Fig. 4 at which time a rod 20 will have 85 moved by gravity along the curved slots 21 in the brackets 21^a which is also fixed upon the rail 10, into the position shown by Fig. 4 and will have carried with it the threads of 90 yarn 6^b extending from the bobbins 6 so that any of such threads 6^b which might have encircled the ends of the spindles 4 as they were being uncoiled from their bobbins 6 (somewhat as is shown by Fig. 3) will by 95 the descending movement of the rod 20 be carried beyond the ends of the spindle 4, thus leaving said thread free to be acted upon as is well known.

The attendant then operates the handle 12 so as to bring the spindles 4 into the position shown by Fig. 5 in which said spindles are in perfect alignment with pegs 16 upon which the empty bobbins 6^d are situated. When the spindles 4 are thus in alignment with the pegs 16 the attendant then revolves 100 the hand wheel 17 which (by well known gearing) raises the racks 18 so that a thread cutter 19 mounted at the upper ends of said racks 18 will come in contact with the lower ends of the bobbins 6^d and raise said bobbins 110 on to the spindles 4 on which the shoes or bobbin holders 8 will again be operated by the handle 15 to cause said holders to pass beneath the bases of the empty bobbins 16 and retain them on the spindles 4. After 115 this adjustment of the empty bobbins the attendant will readjust the lifter rail 5 and then will further move back the spindles 4 and the bobbin holders 8 from the position shown in Fig. 3 to the position shown in Fig. 6 this being effected by the usual and well known handle devices which are operated in the manner hereinbefore explained.

On the parts being readjusted in the positions shown by Fig. 6 the attendant will then 125 operate the handle 40 to readjust the rail B in its position for its foot-step bearings to support the spindles 4. He will then operate the hand wheel 17 to raise the racks 18 in order to lift the thread cutter 19 into the 130

position shown by said Fig. 6 so that on the machine being started into motion the attendant may slide said thread cutter in known manner lengthwise the machine to sever the threads after same have been wound for the desired number of turns or coils around the bobbin 6^a, by the commencement of the spinning operations.

The form of foot-step bearing 44 which we employ is produced by a body member having an inner member 44^a forced into a central opening made axially therein. The inner member has its upper part of less diameter than the part below so that an inner annular space *w* is formed at this part to receive lubricant which will flow over the upper end to enter the cavity *x* where the end of the spindle is supported and where it rotates. The body member is mounted in an opening made in the step rail B and is held against rotation by a screw 45, while by the nut 46 taking over the screwed part of the member 44, this latter may be adjusted vertically to meet any of the requirements of the spindle 4.

Such being the nature of our said invention what we claim is:—

1. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for moving said lifter rail longitudinally, washer holders mounted upon so as to move with and as the lifter rail moves, bobbin holders arranged to take beneath the bases of the bobbins, means for operating said holders, a series of fixed pegs arranged to receive the empty bobbins, another series of pegs arranged to receive the full bobbins, an oscillating rail upon which said pegs are fixed, devices for placing the empty bobbins upon their spindles and means for severing the threads.

2. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for moving said lifter rail longitudinally, washer holders mounted upon so as to move with and as the lifter rail moves, projections extending vertically from said holders in order to retain the washers laterally and lateral projection from said holders to take into the openings in the lifter rail, bobbin holders arranged to take beneath the bases of the bobbins, means for operating said holders, a series of fixed pegs arranged to receive the empty bobbins, another series of pegs arranged to receive the full bobbins, an oscillating rail upon which said pegs are fixed, devices for placing the empty bobbins upon their spindles and means for severing the threads.

lating rail upon which said pegs are fixed, devices for placing the empty bobbins upon their spindles and means for severing the threads.

3. In spinning and like machines having doffing mechanism, rotary spindles having upper and lower bearings, fliers fixed on said spindles, an oscillating rail to which the upper bearings for the spindles are fixed, means for oscillating said rail a lower or step rail for supporting the lower bearings for the spindles, said bearings, means for adjusting and securing said bearings, a lifter rail through which the spindles take, means for moving said lifter rail longitudinally, washer holders mounted upon so as to move with and as the lifter rail moves, bobbin holders arranged to take beneath the bases of the bobbins, means for operating said holders, a series of fixed pegs arranged to receive the empty bobbins, another series of pegs arranged to receive the full bobbins, an oscillating rail upon which said pegs are fixed, devices for placing the empty bobbins upon their spindles and means for severing the threads.

4. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for moving said lifter rail longitudinally, washer holders mounted upon so as to move with and as the lifter rail moves, bobbin holders arranged to take beneath the bases of the bobbins, means for operating said holders, a series of fixed pegs arranged to receive the empty bobbins, a thread cutter arranged in position adjoining said series of fixed pegs, means for raising said thread cutter to enable it to place the empty bobbins on the spindles, another series of pegs arranged to receive the full bobbins, an oscillating rail upon which said pegs are fixed, devices for placing the empty bobbins upon their spindles and means for severing the threads.

5. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for moving said lifter rail longitudinally, washer holders mounted upon so as to move with and as the lifter rail moves, bobbin holders arranged to take beneath the bases of the bobbins, means for operating said holders, a series of fixed pegs arranged to receive the empty bobbins, a thread cutter arranged in position adjoining said series of fixed pegs, vertically movable racks for

supporting and operating the thread cutter, means for operating the thread cutter to cut the threads, another series of pegs arranged to receive the full bobbins, an oscillating rail upon which said pegs are fixed, devices for placing the empty bobbins upon their spindles and means for severing the threads.

6. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for moving said lifter rail longitudinally, washer holders mounted upon so as to move with and as the lifter rail moves, bobbin holders arranged to take beneath the bases of the bobbins, means for operating said holders, a series of fixed pegs arranged to receive the empty bobbins, another series of pegs arranged to receive the full bobbins, an oscillating rail upon which said pegs are fixed, brackets carried by said oscillating rail having curved slots formed in them, a rod taking through the curved slots in said

brackets, devices for placing the empty bobbins upon their spindles and means for severing the threads.

7. In spinning and like machines having doffing mechanism, rotary spindles having upper and lower bearings, fliers fixed on said spindles, an oscillating rail to which the upper bearings for the spindles are fixed, means for oscillating said rail, a lifter rail through which the spindles take, means for operating said lifter rail, drag devices carried by said lifter rail, a series of pegs arranged to receive the empty bobbins, another series of pegs arranged to receive the full bobbins, an oscillating rail upon which said latter pegs are fixed, brackets upon said oscillating rail, a bar loosely carried by said brackets for acting upon the threads when the rail is oscillated into the position described, devices for placing the empty bobbins upon their spindles and means for severing the threads.

ALFRED STELL.
